UNITED STATES PATENT OFFICE.

GUSTAVE M. NELL, OF DENVER, COLORADO, ASSIGNOR TO THE DENVER ROCK DRILL MANUFACTURING COMPANY, OF DENVER, COLORADO, A CORPORATION OF DELAWARE.

MEANS FOR OPENING THE BORES OF STEELS FOR ROCK-DRILLING PURPOSES.

Application filed May 21, 1918. Serial No. 235,821.

In the manufacture, repair and sharpening of drill steels of that type having longitudinal bores therethrough, it is, of course, necessary that the bores of the completed 5 steel be fully open. In some types of steel, lugs are formed at one end, and the formation and the sharpening of the bits tend to close the openings or bores.

The primary object of the present invention is to provide means for opening and properly gauging the ends of the bores, and a further object is to so construct the mechanism that it is compact and can be utilized as an attachment or adjunct to a drill sharpening apparatus.

In the accompanying drawings:

Figure 1 is a view in elevation of a portion of a well known type of drill sharpener, showing the bore opening means in place 20 thereon,

Figure 2 is a longitudinal sectional view through the operating mechanism,

Figure 3 is a rear end elevation,

Figure 4 is a cross sectional view on the 25 line 4-4 of Figure 2,

Figures 5 and 6 are sectional views taken respectively on the lines 5-5 and 6-6 of Figure 4.

Figure 7 is a front elevation of a well 30 known type of drill sharpening machine showing the invention mounted thereon.

Similar reference numerals designate corresponding parts in all the figures of the drawings.

A portion of the base of a well known 35 type of drill sharpener is shown at 7. Said sharpener employs relatively movable jaw elements 8 and 9 for securing the drill steels during the sharpening operations. In this respect they correspond to the elements 9 and 10 disclosed in Patent No. 1,214,604, of February 6, 1917. On one side of these elements are fixed clamping jaws 10 and 11, which are also relatively movable, and are 40 shaped to grip a drill steel, a portion of which is shown at 12. The steel is provided with a longitudinal bore 13 therethrough, and in the manufacture, repair or sharpening, this bore at the ends is apt to be closed.

It is for the purpose of reopening and properly shaping the same that the following mechanism is provided.

Suitably secured to the base 7 at one side of the clamping jaws 10-11 is a bracket 14

fastened by any suitable means, as bolts 15, 55 and projecting beyond the base 7, as clearly shown in Figure 1. Upon the projecting end of this base is bolted, as shown at 16, a mounting 17 supporting a fixed cylinder member or casing 18. The cylinder member 60 is provided with heads 19, and operating therein, is a tubular piston having a plunger head 20 and oppositely extending reduced portions 21 that slidably pass through the heads 19.

The said tubular piston constitutes a cylinder and has an internal piston chamber 22 closed by a front head 23 and by a rear element or block 24, the latter abutting against and being held in place by a tubular plug 70 block forming a rear head 25. The tubular piston or cylinder 20-21 obviously constitutes a connection between the front and rear heads 23 and 25. The front head 23 contains a tappet or front anvil block 26, the rear 75 end of which projects into the chamber 22, the front end projecting beyond the head 23, and having a socket 27 to receive the rear end of a tapered punch pin 28. The tubular piston or cylinder 20-21 therefore constitutes 80 a connection between the element or block 24 and the anvil block or tappet 26 with its punch pin 28. Moreover, the piston 20 constitutes movable means that operates in opposition to the anvil block or tappet 26 and 85 the force of said piston 20 when moving rearwardly is transmitted to the anvil block or tappet and consequently to the punch pin by means of the cylinder 21 and head 23. This 90 pin may be held in place by a transverse key 29, and the arrangement is such that the pin will be aligned with the bore 13 of a drill steel clamped by the jaws 10 and 11, as will be evident by reference to Figure 1. The tappet 26 has an annular flange 30 operating 95 in the chamber 31 formed in the head 23, this chamber having communication with the piston chamber 22 through a passageway 32 and lateral ports 33, which open on opposite sides of the flange 30. A reciprocating hammer piston 34 operates in the chamber 22 and strikes against the rear end of the tappet 26, said piston having a rearward extension or neck 35 that is slidable in the head 24 and projects into the chamber 36 of the plug 25. 100

The mounting 17 is formed with a valve casing having a tapered seat 37, and located in said casing is a rotary throttle valve 38

provided with an actuating handle crank 39. The valve is hollow, as shown at 40, and motive fluid is supplied thereto by any suitable source, through a coupling 41. The 5 valve is provided with a pair of lateral ports 42 that are respectively movable into communication with a supply passageway 43 leading through the bottom of the mounting and having communication with a flexible conduit or hose 44 that is coupled, as 10 shown at 45, to the rear end of the tubular piston 20, and is thus in communication with the chamber 36 of the plug or rear head 25, so that a passageway is thus formed which 15 extends through the cylinder 20—21 and opens into the casing to conduct motive fluid into said cylinder.

From the chamber 36, a passageway 46 leads to an annular groove 47 formed in the 20 head 24 around the piston stem 35, the portion of said stem adjacent to the head 24 having a reduced cross sectional area, so 25 indicated at 48. From the bore of the head 24, through which the stem 35 passes, another passageway 49 leads to a port 50 opening 30 into the front end of the chamber 22. An exhaust port 51 is also in communication with the chamber 22, and opens into an exhaust passageway 52 that has an outlet port 53, to the atmosphere.

It will thus be evident that when the throttle valve 38 is turned so that either port 42 communicates with the passageway 43, motive fluid will enter the chamber 36. When 35 the piston hammer 34 is in the position shown in Figure 2, this motive fluid will flow through the passageway 46 and operate against the rear face of the head 34. The pressure against said head and the constant 40 pressure against the rear end of the stem 35 will drive the piston hammer forwardly, the exhaust in advance of the same taking place through the port 51. A blow will thus be delivered against the tappet 26 and this 45 blow will, of course, be transmitted to the punch pin 28. When the blow takes place, the rear end of the stem 35 of the piston will have traveled sufficiently far to uncover the passageway 49, while the passageway 46 will be closed by the larger portion of said 50 stem. Motive fluid will therefore pass through the passageway 49 and port 50 and operate against the front face of the piston, the area thereof being greater than that of the rear end of the stem 35, and the head 34 having passed the port 51, the exhaust will 55 take place from behind the head 34 and the piston be driven rearwardly.

As indicated in Figures 2 and 6, the 60 mounting 17 is provided with oppositely extending passageways 54 leading from the valve seat 37 and having ports 55 opening into the cylinder member 18 on opposite sides of the piston head 20. The mounting 65 also is provided with oppositely extending

exhaust passageways 56 that open to the atmosphere and communicate with the valve casing below the passageway 54. The valve, as clearly shown in Figures 4 and 6, is provided with a port 57 that is movable into 70 communication with either passageway 54, and likewise has a transversely disposed channel 58 that will afford communication with the corresponding passageways 54 and 56. If therefore the valve 38 is turned in 75 one direction, the port 57 will communicate with one of the supply passageways 54, while the other supply passageway 54 will be brought into communication with the corresponding exhaust passageway 56 by the 80 channel 58. Consequently motive fluid can be supplied to the cylinder member on either side of the piston head 20 by turning the valve in either direction, and as above explained, and as will be clear by reference 85 to Figure 5, this movement will bring one of the ports 42 into communication with the passageway 43, so that motive fluid will be delivered to the hammer piston.

The operation of the apparatus is substantially as follows. When the drill steel has been properly shaped, sharpened or otherwise operated upon, and while its end is still heated sufficiently to permit the working of the metal, it is clamped between the jaws 10 90 and 11. The throttle valve 38 is thereupon turned so that motive fluid will be supplied behind the piston head 20, and this will cause the tubular piston and the pin punch to be advanced to that the free end thereof 100 will enter the bore 13 of the drill steel. At the same time the hammer piston 34 is supplied with motive fluid and will deliver a rapid series of blows against the tappet 26 consequently driving the pin into the bore 105 and properly opening the same. When the operation is completed the valve handle, and consequently the valve, are turned in the opposite direction, whereupon motive fluid will 110 be supplied against the front face of the piston head 20 and the same will be retracted, carrying the pin away from the drill steel. During this operation the action of the hammer is continued, and this has been found advantageous in the extracting of the 115 pin from the steel.

The hammer 34 and its path of movement are shifted with respect to the blow-receiving means, namely, the tappet 26 to change the effect of the hammer blows by relieving 120 the tappet of the blows when the cylinder and hammer are pulled back. The hammer 34 on its backward stroke does not contact with the head or block 24 because prior to 125 its contact the reduced portion 48 of the extension communicates with the supply port 49 and admits motive fluid behind the hammer 34, and thus means are provided for preventing the hammer piston 34 contacting with said block 24.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim is:—

1. In apparatus of the character set forth, the combination with a drill sharpener base and relatively movable drill steel clamping jaw members carried thereby, of supplemental coacting jaws carried by the jaw members, a pin punch for opening the bore of a drill steel placed in the jaws, supported on the base in coacting alignment with the supplemental jaws, means positively connected to the pin punch for causing the advance of the pin punch toward the supplemental jaws and its movement away from the same, said means permitting a limited free movement of the pin punch, and means for automatically delivering rapidly repeated hammer blows upon said pin punch.

2. The combination with a bore opening pin, of a fluid operated reciprocating hammer, a tappet to which the pin is secured, said tappet being movable into and out of the effective path of one end of the hammer on its movement in one direction, a device at the rear end of the hammer and movable to different positions with respect to the tappet, and means connected to said device and movable into abutment with the tappet when the tappet is moved out of the effective path of the hammer.

3. The combination with a fluid operated reciprocating piston hammer, of a chambered head, a tappet movably mounted in the chamber of the head, a bore-opening pin of a size to enter the bore of a drill steel, said pin being fixed to the tappet, said tappet being movable to the rear end of the chamber in a position to receive the direct forward blows of the piston hammer to drive the pin into the bore, a head in rear of the piston hammer and movable toward and from the tappet, and means connected to said head and movable into abutting engagement with the tappet when the tappet is moved to the front portion of the chamber.

4. The combination with a bore-opening pin, of a fluid operated reciprocating hammer, means for receiving the force of the blows of said hammer and delivering them to the pin, and means for shifting the hammer and its path of movement with respect to said blow receiving means to change the effect of the hammer blows on the pin.

5. The combination with a bore-opening pin, of a fluid operated reciprocating hammer, means for receiving the force of the

blows of said hammer and delivering them to the pin, and fluid operated means for shifting the hammer and its path of movement to change the effect of the hammer blows on the pin.

6. The combination with a tappet, of means for securing a bore-enlarging pin thereto, a reciprocatory piston hammer, means for holding the tappet in position to be struck directly by the hammer on its movements in one direction, movable means operating in opposition to the tappet, means for transmitting force from said means to the tappet, and means for relatively changing both the tappet and opposing means and the path of the piston hammer to cause the latter to effectively deliver the kinetic energy of the blows of said hammer either directly to said tappet or relieve it from said direct blows.

7. The combination with a reciprocatory piston hammer, of a chambered head in advance of the same, a reciprocable tappet mounted in the head and having a flange in the chamber that limits the movement of said tappet, a bore-enlarging pin fixed to the tappet and projecting beyond the head, said piston hammer in its forward movement being adapted to strike the rear end of the tappet when the flange thereof is at the rear end of the chamber, an oppositely disposed means in rear of the piston hammer, means connected to the head and to the oppositely disposed means, and fluid-operated means for shifting the piston hammer and its path of movement to cause the said hammer to either strike the tappet directly and deliver forward blows thereto or relieve said tappet of said blows and causing the head to be abutted against the tappet.

8. The combination with a fluid operated reciprocating hammer, of a tappet movable into and out of the range of the hammer, means for detachably fixing a drill steel pin punch to said tappet so as to move therewith, means for causing said hammer to deliver the kinetic energy of a series of blows to said tappet to effect the movement of the tappet in a direction to drive the pin punch into the bore of a drill steel, and means movable into abutting relation with a front face of the tappet when the tappet is moved out of direct range of the hammer, said means having a portion located at the rear of the hammer.

9. The combination with a fluid operated reciprocating hammer, of a tappet movable into and out of the range of the hammer, a cylinder member housing both hammer and tappet and permitting their independent and their relative play, means for detachably fixing a drill steel pin punch to the tappet to move therewith, and means for moving the cylinder member in opposite directions and delivering fluid to the hammer to cause it

to operate on the tappet when the cylinder is moved in one direction.

10. The combination with a cylinder member movable in opposite directions, of a tappet movably mounted in one end of the same, means carried by the cylinder member for limiting said movement and causing the tappet to be moved in opposite directions with the cylinder member, said tappet having a socket for a pin punch, means for detachably securing a drill steel pin punch in the socket of the tappet, a fluid operated piston hammer in the cylinder member and adapted to deliver blows to the tappet, and means for causing said hammer to operate during the movement of the cylinder member in either of opposite directions.

11. In apparatus of the character set forth, the combination with a pin punch for opening the bore of a drill steel of a movable clamp for holding drill steels in position to receive the pin punch, means connected to the punch for moving the punch both toward and from the clamp, a fluid actuated hammer, means for supplying motive fluid to the hammer to cause its rapid rectilinear reciprocation, when the punch is engaged in the bore of the drill steel both during its movements toward and from the clamp.

12. In apparatus of the character set forth, the combination with a base, of a drill steel clamp mounted on the base, a bracket on the base, a pin punch for opening the bore of a drill steel placed in the clamp, means on the bracket and positively connected to the punch for moving the punch both toward and from the clamp, a fluid actuated hammer, and means for supplying motive fluid to the hammer to cause its rapid reciprocation when the punch is engaged in the bore of the drill steel both during its movements toward and from the clamp.

13. In apparatus of the character set forth, the combination with a pin punch for opening the bore of a drill steel of a movable clamp for holding drill steels in position to receive the pin punch, fluid actuated means connected to the punch both for advancing the punch toward and withdrawing it away from the clamp, a fluid actuated hammer carried by said means, and means for supplying motive fluid to the hammer to cause its rapid reciprocation when the punch is engaged in the bore of the drill steel both during its movements toward and from the clamp under the action of the fluid actuated means.

14. In apparatus of the character set forth, the combination with a base, of a drill steel clamp mounted on the base, a bracket on the base, a pin punch for opening the bore of a drill steel placed in the clamp, a cylinder mounted on the bracket, a tubular piston operating in the cylinder, means for supply-

ing motive fluid to the cylinder to move the piston, a tappet mounted in the piston and having means for holding the punch, a fluid actuated hammer piston within the tubular piston and within the cylinder, and means for supplying motive fluid to the tubular piston to actuate the hammer piston, both during the movements of the punch toward and from the clamp.

15. In apparatus of the character set forth, the combination with a base, of a drill steel clamp mounted thereon, a bracket projecting from the base, a cylinder member, a mounting for securing the cylinder member to the bracket, said mounting having a valve casing, a tubular piston operating in the cylinder member, passageways for delivering motive fluid from the valve casing to the cylinder member against opposite faces of the tubular piston, a tappet located in one end of the tubular piston and including a tool socket, a pin punch in the tool socket adapted to enter and open the bore of a drill steel placed in the clamp, a hammer piston in the tubular piston and within the cylinder and separate from and operating on the tappet, means for supplying motive fluid from the valve casing to the tubular piston and distributing it to the hammer piston for continuously operating the latter, means for transmitting the kinetic energy of the rapidly repeated blows of the hammer to the punch, and a valve for controlling the passageways and supply means.

16. In apparatus of the character set forth, the combination with a punch pin for operating in the bore of a steel of a movable clamping means in advance of the pin for holding steels in position to receive the pin, power operated means engaged with the punch pin for advancing it into and withdrawing it from said bore, a powder operated hammer and means for operating the hammer both during the advancement and withdrawal of the punch-pin by said means.

17. In apparatus of the character set forth, the combination with a drill steel clamp, comprising relatively movable clamping members of a punch pin for operating in the bore of a steel clamped thereby, fluid operated means for automatically delivering rapidly repeated hammer blows to the punch pin, fluid operated means for advancing the punch pin toward the clamp and withdrawing it away from the same while the hammer is in rapid movement, and means supporting the said fluid operated means both in its advancing and withdrawing movements.

18. In apparatus of the character set forth, the combination with a drill steel clamp, comprising relatively movable clamping jaws of a punch pin for operating in the bore of a steel clamped thereby, a support, fluid operated means movably mounted on the support for automatically delivering

- rapidly repeated hammer blows, fluid operated means connected to the pin punch for advancing the punch pin toward the clamp and positively withdrawing it away from the same while the hammer is in rapid movement, means for supplying motive fluid to both the hammer and the moving means, and a common valve for controlling the supply of motive fluid to both.
19. In apparatus of the character set forth, the combination with a drill steel clamp, comprising relatively movable clamping jaws of a punch pin for operating in the bore of a steel clamped thereby, a fixed support adjacent the steel clamp, fluid operated means for automatically delivering rapidly repeated hammer movements, fluid operated means on the support connected to the pin punch for advancing the punch pin toward the clamp and positively withdrawing it away from the same while the hammer is in action, means for supplying motive fluid to both the hammer and the moving means, a common valve for controlling the supply of motive fluid to both, and means for causing the hammer to be operated to assist the fluid operated feeding means to move the pin punch both in the advancing and withdrawal movements of the same by the fluid operated means.
20. In apparatus of the character set forth, the combination with a drill sharpener base and relatively movable drill steel clamping jaw members carried thereby, of supplemental coacting jaws carried by the jaw members at one side of the same, a pin punch supported on the base out of line with the jaw members but in coacting alignment with the supplemental jaws, and means for causing the advance of the pin punch toward the supplemental jaws and its movement away from the same.
21. In apparatus of the character set forth, the combination with a drill sharpener base and relatively movable drill steel clamping jaw members carried thereby, of supplemental coacting jaws carried by the jaw members on one side of the same, a bracket secured to the base, a pin punch mounted on the bracket in coacting alignment with the supplemental jaws and out of alignment with the jaw members, and means for causing the pin punch to be advanced to enter and open the bore of a drill steel secured by the supplemental jaws.
22. The combination with a bore opening pin, of a fluid operated reciprocating hammer movable with respect to the pin, means for causing said hammer to impart a series of driving blows to said pin longitudinally thereof to drive it into the bore to be opened and for causing a series of complete full speed movements of the hammer when the pin is withdrawn from said bore after it has been driven thereinto, said hammer during its movement between the limits of its stroke being free from the pin.
23. The combination with a bore opening pin, of a fluid operated reciprocating hammer movable with respect to the pin, and means for transmitting to the pin longitudinally thereof a series of blows from one end of said hammer to drive the pin into a bore and for causing a series of full speed movements of the hammer when the pin is pulled out of the bore after it has been driven thereinto, said hammer during its movement between the limits of its stroke being free from the pin.
24. In a shank and bit punch, the combination with a drill steel clamp, of a pin punch for opening the bore of a drill steel placed in the clamp, a stationary casing, a hammer cylinder having a plunger head movable forwardly and rearwardly in said casing by fluid pressure for advancing the punch toward and withdrawing it away from the clamp, a fluid actuated piston hammer in said cylinder for delivering repeated blows to the punch when engaged in the bore of the drill steel, and means including a valve for distributing motive fluid to the casing and to the said cylinder through said casing.
25. In a shank and bit punch, the combination with a drill steel clamp, of a pin punch for opening the bore of a drill steel placed in the clamp, a stationary casing, means for fixedly mounting the same in spaced relation to the clamp, a hammer cylinder having a plunger head movable forwardly and rearwardly in said casing by fluid pressure for advancing the punch toward and withdrawing it away from the clamp, a fluid actuated piston hammer in said cylinder for delivering repeated blows to the punch when engaged in the bore of the drill steel, and means including a valve for distributing motive fluid to the casing and to said cylinder forwardly of said plunger head.
26. In a shank and bit punch, the combination with a drill steel clamp, of a pin punch for opening the bore of a drill steel placed in the clamp, a stationary casing, a hammer cylinder having a plunger head movable forwardly and rearwardly in said casing by fluid pressure for advancing the punch toward and withdrawing it away from the clamp, a fluid actuated piston hammer in said cylinder for delivering repeated blows, means for causing the force of said blows to be transmitted to the punch when engaged in the bore of the drill steel, a passageway through said cylinder opening into the casing to conduct motive fluid into said cylinder, and means including a valve and said passageway for distributing motive fluid to one side of said plunger head during the movement of the hammer cylinder.

in one direction while constantly supplying motive fluid to actuate the piston hammer to cause it to automatically and rapidly reciprocate on both the forward and the rearward movements of the hammer cylinder.

27. In a shank and bit punch, the combination with a drill steel clamp, of a pin punch for opening the bore of a drill steel placed in the clamp, a stationary casing, a hammer cylinder having a plunger head movable forwardly and rearwardly in said casing by fluid pressure for advancing the punch toward and withdrawing it away from the clamp, a fluid actuated piston hammer in said cylinder for delivering repeated blows, means for causing the force of said blows to be transmitted to the punch when engaged in the bore of the drill steel, a passageway through said cylinder opening into the casing to conduct motive fluid into said cylinder, and means including a valve and said passageway for distributing motive fluid behind said plunger head during the movement of the hammer cylinder in one direction, while constantly supplying motive fluid to actuate the piston hammer to cause it to rapidly reciprocate on both the forward and the rearward movements of the hammer cylinder.

30. 28. In a shank and bit punch, the combination with a drill steel clamp, of a pin punch for opening the bore of a drill steel placed in the clamp, a stationary casing, a hammer cylinder having a plunger head movable forwardly and rearwardly in said casing by fluid pressure for advancing the punch toward and withdrawing it away from the clamp, a fluid actuated piston hammer in said cylinder, means for delivering the force of the repeated blows of the piston hammer to the punch when engaged in the bore of the drill steel, a passageway through said cylinder opening into the casing to conduct motive fluid into said cylinder, and means including a valve and said passageway for distributing motive fluid in front of said plunger head during the movement of the hammer cylinder in one direction while constantly supplying motive fluid to actuate the piston hammer to cause it to rapidly reciprocate on both the forward and the rearward movements of the hammer cylinder.

29. In a shank and bit punch, the combination with a drill steel clamp, of a pin punch for opening the bore of a drill steel placed in the clamp, a stationary casing, a hammer cylinder having a plunger head movable forwardly and rearwardly in said casing by fluid pressure for advancing the punch toward and withdrawing it away from the clamp, a fluid actuated piston hammer in said cylinder, a passageway through said cylinder opening into the casing to conduct motive fluid into said cylinder, and

means including a valve and said passageway for distributing motive fluid to said plunger head to effect the movement of the hammer cylinder in one direction, while constantly supplying motive fluid to actuate the piston hammer to cause it to automatically deliver repeated blows in rapid succession during such movement of the hammer cylinder.

30. In a shank and bit punch, the combination with a drill steel clamp, of a pin punch for opening the bore of a drill steel placed in the clamp, a casing, a hammer cylinder having a plunger head, a fluid actuated piston hammer in said cylinder for delivering repeated blows, passageways leading to said casing rearwardly of the said cylinder plunger head and through said casing to the interior of said cylinder, a valve for connection to a source of motive fluid supply and having alternate positions whereby motive fluid may be introduced simultaneously to said cylinder plunger head and interior of the cylinder in one position of the valve and exhausted from the casing at one side of said plunger head and admitted to the other side of said plunger head in another position of said valve.

31. In a shank and bit punch, the combination with a drill steel clamp, of a pin punch for opening the bore of a drill steel placed in the clamp, a casing, a cylinder within said casing having a plunger head and guided in said casing at one end, a hammer piston within said cylinder for delivering repeated blows, passageways in said casing leading to the front of the plunger head and to the interior of the cylinder for the introduction of motive fluid to said cylinder, a passageway in said casing rearwardly of said plunger head, and a valve associated with all said passageways and having alternate operating positions in both of which access is had by motive fluid to the cylinder and in only one of which access is had by motive fluid to the casing rearwardly of said plunger head.

32. In a shank and bit punch, the combination with a fixed casing, of a cylinder mounted to reciprocate in the casing and having a plunger head also in the casing, a piston hammer located in the portion of the cylinder that is in the casing, a pin punch for opening the bore of a drill steel, movably carried by the cylinder and projecting beyond the casing, said pin punch being operated on by the piston hammer, a controlling valve, and passageways in the casing controlled by the valve and leading from the valve to the interior of the casing in advance of and behind the plunger head and through the cylinder member to supply motive fluid thereto.

33. In a shank and bit punch, the combination with a fixed casing, of a cylinder

movably located in the casing and having an external plunger head in the casing, an anvil block movably mounted in one end of the cylinder, a pin punch for opening the bore 5 of a drill steel detachably fixed to the outer end of the anvil block and projecting beyond the cylinder and casing, a piston hammer within the cylinder that strikes the anvil block and has means for distributing motive 10 fluid to effect its own operation, passageways formed in the casing and through the cylinder for delivering motive fluid to the interior of the casing on opposite sides of the plunger head and to the interior of the cylinder 15 for supplying motive fluid to the hammer piston, and a single valve controlling the passageways.

34. In a shank and bit punch, the combination with a fixed casing, of a cylinder 20 movably located in the casing and having an external plunger head in the casing, an anvil block movably mounted in one end of the cylinder, a pin punch for opening the bore of a drill steel detachably fixed to the outer end of the anvil block and projecting beyond the cylinder and casing, a piston hammer within the cylinder that strikes the anvil block and has means for distributing motive 25 fluid to effect its own operation, passageways formed in the casing and through the cylinder for delivering motive fluid to the interior of the casing on opposite sides of the plunger head and to the interior of the cylinder for supplying motive fluid to the hammer piston, and a single valve controlling the passageways and admitting motive 30 fluid to the interior of the cylinder both when motive fluid is being admitted to the interior of the casing in front of and behind the plunger head.

35. In a shank and bit punch, the combination with a fixed casing, of a cylinder movably located in the casing and having an external plunger head in the casing, an anvil 45 block movably mounted in one end of the cylinder, a pin punch for opening the bore of a drill steel detachably fixed to the outer end of the anvil block and projecting beyond the cylinder and casing, a piston hammer within the cylinder that strikes the anvil block, a valve chamber, a passageway extending from the valve chamber through the casing and to the interior of the cylinder for supplying motive fluid to operate the piston hammer, a passageway in the casing leading from the valve chamber to the interior of the casing in rear of the plunger head, an exhaust passageway leading from the valve chamber, and a valve in the valve chamber 55 that is movable to a position to supply motive fluid to the passageway leading to the rear of the plunger head and to another position to connect said passageway to the exhaust, said valve in both positions admitting motive fluid to the cylinder.

36. In a shank and bit punch, the combination with a fixed casing, of a cylinder movably located in the casing and having an external plunger head in the casing, an anvil block movably mounted in one end of the cylinder, a pin punch for opening the bore of a drill steel detachably fixed to the outer end of the anvil block and projecting beyond the cylinder and casing, a piston hammer within the cylinder that strikes the anvil block, a valve chamber in the casing below the cylinder, a passageway extending from the valve chamber through the casing and to the interior of the cylinder for supplying motive fluid to operate the piston hammer, a passageway in the casing leading from the valve chamber to the interior of the casing in rear of the plunger head, an exhaust passageway leading from the valve chamber, and a valve in the valve chamber that is movable to a position to supply motive fluid to the passageway leading to the rear of the plunger head and to another position to connect said passageway to the exhaust, said valve in both positions admitting motive fluid to the cylinder.

37. In a fluid actuated machine for punching hollow articles, the combination of a cylinder and reciprocating hammer piston, elements separate from the piston at each end of the cylinder, one element being adapted to carry a pin, and means for causing the piston on its reciprocation to deliver its kinetic energy to one of the said elements or relieve said element therefrom according to the direction in which the pin is to be moved.

38. In a fluid actuated machine for punching hollow articles, the combination of a fixed cylinder or casing and reciprocating hammer piston, elements separate from the piston at each end of the cylinder or casing, one element being adapted to carry a pin, front and rear heads movable relatively to the cylinder or casing, and means for moving said heads to bring said elements into different positions with respect to the pin-carrying element according to the direction in which the pin is moved.

39. In a fluid actuated machine for punching hollow articles, the combination of a cylinder or casing and reciprocating hammer piston, front and rear elements separate from the piston, the front element being adapted to carry a pin, a front head and a rear head for the cylinder or casing, other front and rear heads connected together and movable relatively to said first front and rear heads, and means for moving said latter heads to bring the rear element to different portions with respect to the front element according to the direction in which the pin is to be moved.

40. In a fluid actuated machine for punching hollow articles, the combination of a cylinder or casing and reciprocating

piston, spaced elements, one of said elements being adapted to carry a pin, a front head and a rear head for the cylinder or casing in which the said elements are movable, other front and rear heads connected together and movable relatively to said front and rear cylinder heads, said second heads being associated with the elements, and means for moving said second heads to bring the pin-carrying element into different positions with respect to the path of the piston according to the direction in which the pin is to be moved.

41. In a fluid actuated machine for punching hollow articles, the combination of a cylinder or casing and a double ended reciprocating hammer piston, elements separate from the piston at the opposite ends of and in line with the hammer piston, one element being adapted to carry a pin, heads movable with respect to the cylinder or casing and associated with the respective elements, and means connecting said heads to effect their movements to different positions with respect to the pin carrying element according to the direction in which the pin is moved.

42. In a fluid actuated machine for punching hollow articles, the combination with a cylinder or casing, of spaced heads movable with relation to the cylinder or casing, a connection between the heads that is reciprocable with respect to the cylinder or casing, an anvil block movably mounted in one of the heads and adapted to carry a pin, a separate element spaced from the anvil block and abutting against the other head, and a hammer piston operating between the anvil block and element and adapted to impart blows of impact to one and relieve it of said blows according to their respective positions and the direction in which the pin is moved.

43. In a fluid actuated machine for punching hollow articles, the combination with a cylinder or casing, of spaced front and rear heads movable with relation to the cylinder or casing, a connection between the heads that is reciprocable with respect to the cylinder or casing, an anvil block movably mounted in the front head and adapted to carry a pin, a separate element spaced from the anvil block and abutting against the rear head, and a double-ended hammer piston operating between the anvil block and element and adapted to impart its kinetic energy to one or relieve it therefrom according to their respective positions and the direction in which the pin is moved.

44. In a fluid actuated machine for punching hollow articles, the combination with a cylinder or casing, of spaced heads movable with relation to the cylinder or casing, a connection between the heads that is reciprocable with respect to the cylinder or cas-

ing, an anvil block movably mounted in one of the heads and adapted to carry a pin, a separate element spaced from the anvil block and abutting against the other head, a double-ended hammer piston operating between the anvil block and element and adapted to impart kinetic energy repeatedly to one according to their respective positions and the direction in which the pin is moved, and means for moving said head and connections to change the positions of the anvil block with respect to the travel of the piston.

45. In a fluid actuated machine for punching hollow articles, the combination with a fixed cylinder or casing, of fixed heads therefor, a reciprocable member mounted on the casing and having spaced heads, an anvil block mounted in one of the latter heads and capable of limited movement therein, said anvil block being adapted to carry a pin, an element spaced from the anvil block and abutting against the other head, a fluid operated hammer piston separate from but located between the anvil block and element and adapted to impart or not impart kinetic energy to one accordingly as the heads and connection are shifted with respect to the cylinder or casing.

46. In a fluid actuated machine for punching hollow articles, the combination with a drill steel clamp, of a cylinder and reciprocating hammer piston, a block at each end of the cylinder, one block being adapted to carry a pin for opening the bore of a drill steel placed in the clamp, means for causing the hammer piston to impart or not impart its kinetic energy to one of the said blocks according to the direction in which the pin is to be moved in the drill steel, fluid actuated means for feeding the machine forwardly towards the clamp and for retracting the machine away from the clamp, and means for controlling the distribution of motive fluid to both the hammer cylinder and the feeding mechanism, to cause the hammer piston to automatically deliver repeated blows in rapid succession while feeding is taking place.

47. In a fluid actuated machine for punching hollow articles, the combination with a drill steel clamp, of a cylinder and reciprocating hammer piston, a block at each end of the cylinder, one block being adapted to carry a pin for opening the bore of a drill steel placed in the clamp, means for causing the hammer piston to impart or not impart its kinetic energy to one of the said blocks according to the direction in which the pin is to be moved in the drill steel, fluid actuated means for feeding the machine forwardly toward the clamp and for retracting the machine away from the clamp, a common valve controlling the supply of motive fluid, and ports and passages leading from the said valve to both the hammer cyl-

inder and the feeding mechanism, whereby the operations of the piston and feeding are simultaneous and controlled by the same valve, both in the advancing and withdrawal movements.

48. In a fluid actuated machine for punching hollow articles, the combination with a drill steel clamp, of a cylinder and valveless differential reciprocating hammer piston having a head and a shank, a block at each end of the cylinder, one block being adapted to carry a pin for opening the bore of a drill steel placed in the clamp, means for causing the hammer piston to impart or not impart the kinetic energy of its repeated blows to one of the said blocks according to the direction in which the pin is to be moved in the drill steel, and automatic fluid actuated feeding mechanism for the machine, whereby the hammer piston will automatically and rapidly reciprocate while feeding is taking place either forwardly or backwardly.

49. In an apparatus of the character set forth, the combination with a drill steel clamp, of a pin punch for opening the bore of a drill steel placed in the clamp, fluid actuated means for advancing the punch toward and withdrawing it away from the clamp, a hammer cylinder carried by said means having a block at each end, one block carrying the pin punch, a hammer piston in the cylinder for delivering the kinetic energy of its repeated blows to one of the said blocks when the punch is engaged in the bore of the drill steel, and means for supplying motive fluid to the hammer to cause it to automatically deliver such repeated blows in rapid succession.

50. In apparatus of the character set forth, the combination with a drill steel clamp, of a punch pin for operating in the bore of a drill steel clamped thereby, fluid operated means for automatically delivering rapidly the force of its repeated blows to the punch pin, comprising a cylinder having a block at each end, one block carrying the punch pin, and a hammer piston in the cylinder, and fluid operated means for advancing the punch pin toward the clamp and withdrawing it away from the same while the hammer is in action.

51. In apparatus of the character set forth, the combination with a drill steel clamp, of a punch pin for operating in the bore of a steel clamped thereby, fluid operated means for automatically delivering the force of its rapidly repeated hammer blows to the punch pin, comprising a cylinder having a block at each end, one block carrying the punch pin, and a hammer piston in the cylinder, fluid operated means for advancing the punch pin toward the clamp and withdrawing it away from the same while the hammer is in action, means for supply-

ing motive fluid to both the hammer and the moving means, and a common valve for controlling the supply of motive fluid to both.

52. In apparatus of the character set forth, the combination of a drill steel clamp, a punch pin for operating in the bore of a drill steel clamped thereby, fluid operated means for automatically delivering the force of rapidly repeated hammer blows to the punch pin, comprising a cylinder having a block at each end, one block carrying the punch pin, and a hammer piston in the cylinder, fluid actuated means for advancing the punch pin toward the clamp and withdrawing it away from the same while the hammer is in action, means for supplying motive fluid to both the hammer and the moving means, and a common valve for controlling the supply of motive fluid to both, and permitting the simultaneous action of the hammer and moving means both in the advancing and withdrawal movements.

53. In apparatus of the character set forth, the combination with a drill steel clamp, of a pin punch for opening the bore of a drill steel placed in the clamp, means positively connected to the punch for moving the punch both toward and from the clamp, a fluid actuated hammer mechanism for delivering the force of repeated blows to the punch when engaged in the bore of the drill steel, said mechanism comprising a cylinder having a block at each end, and a reciprocating hammer piston in the cylinder, and means for supplying motive fluid to the hammer to cause it to automatically deliver such repeated blows in rapid succession.

54. In a fluid actuated machine for punching hollow articles, the combination with a cylinder and reciprocating piston bodily movable toward and from the article to be punched, of a block at each end of the cylinder, one block being adapted to carry a pin, means for causing the piston to impart or not impart the kinetic energy of its blows to one of the said blocks according to the direction in which the pin is to be driven, fluid actuated means for feeding the machine forwardly and for retracting the machine, and manually actuated means for controlling the distribution of motive fluid to both the punching machine and the feeding mechanism.

55. In a fluid actuated machine for punching hollow articles, the combination with a cylinder and reciprocating piston bodily movable toward and from the article to be punched, of a block at each end of the cylinder, one block being adapted to carry a pin, means for causing the piston to impart or not impart the force of its blows to one of the said blocks according to the direction

in which the pin is to be driven, fluid actuated means for feeding the machine forwardly and for retracting the machine, a manually actuated valve controlling the supply of motive fluid, and ports and passages leading from the said valve to both the punching machine and the feeding mechanism, whereby the operations of punching and feeding are controlled by the same valve.

56. In a fluid actuated machine for punching hollow articles, the combination with a cylinder and reciprocating piston bodily movable toward and from the article to be punched; of a block at each end of the cylinder, one block being adapted to carry a pin, means for causing the piston to impart or not impart the force of its blows to one of the said blocks according to the direction in which the pin is to be driven, fluid actuated means for feeding the machine forwardly and for retracting the machine, a valve controlling the supply of motive fluid, ports and passages leading from the said valve to both the punching machine and the feeding mechanism, whereby the operations of punching and feeding are controlled by the same valve, and a hand lever for actuating said valve.

57. In a fluid actuated machine for punching hollow articles, the combination with a cylinder bodily movable toward and from the article to be punched; and a valveless differential reciprocating piston in said cylinder having a head and a shank, of a block at each end of the cylinder, one block being adapted to carry a pin, means for causing the piston to impart or not impart the force of its blows to one of the said blocks according to the direction in which the pin is to be driven, automatic fluid actuated feeding mechanism for the machine, and a motive fluid controlling valve for the punching mechanism and feeding mechanism mounted on a portion of the machine.

58. In a fluid actuated machine for punching hollow articles, the combination with a drill steel clamp, of a cylinder and reciprocating piston, a block at each end of the cylinder, one block being adapted to carry a pin for opening the bore of a drill steel placed in the clamp, means for causing the hammer piston to impart or not impart the kinetic energy of repeated blows to one of the said blocks according to the direction in which the pin is to be driven either into or out of the drill steel, fluid actuated means for feeding the machine forwardly toward the clamp and for retracting the machine away from the clamp, a common valve controlling the supply of motive fluid, and ports and passages leading from the said valve to both the hammer cylinder and the feeding mechanism, whereby the operations of

punching and feeding are controlled by the same valve.

59. In a chuck and bit punch for drill steels, the combination of means for holding the drill steel, a hammer cylinder, an anvil block mounted in said cylinder, a pin carried by said anvil block and adapted to enter the drill steel, a fluid actuated reciprocating hammer piston in said cylinder adapted to hammer the pin into the drill steel by repeated blows against the anvil block in one direction, means for pulling on the cylinder to extract the pin from the drill steel and means for continuing the operation of the hammer piston to assist in withdrawing the pin out of the drill steel.

60. In apparatus of the character set forth, the combination with means for holding the drill steel, of a hammer cylinder, an anvil block mounted in said cylinder, a pin carried by said block and adapted to enter the drill steel, a fluid actuated hammer piston in said cylinder adapted to hammer the pin into the drill steel by repeated blows against the anvil block in one direction, means connected to the anvil block and located in rear of the hammer piston to assist in withdrawing the pin from the drill steel, and means for preventing the hammer piston contacting with said latter means.

61. In apparatus of the character set forth, the combination with means for holding the drill steel of a hammer cylinder, an anvil block mounted in said cylinder, a pin carried by said block and adapted to enter the drill steel, a fluid actuated hammer piston in said cylinder adapted to hammer the pin into the drill steel by repeated blows against the anvil block in one direction, a block connected to the anvil block and located in rear of the hammer piston, and means for preventing the hammer piston contacting with said block.

62. In apparatus of the character set forth, the combination with means for holding a pin punch, and means for holding a drill steel with its bore in line with the pin punch, of a hammer piston, an anvil block carrying the pin punch and movable into and out of the path of one end of the hammer piston, a block at the opposite end of the piston connected to the pin punch and movable to and from a position at different distances from the anvil block, and means for preventing the hammer piston contacting with said block when moved to its nearer said position.

63. In apparatus of the character set forth, the combination with a punch pin carrier and a punch pin mounted thereon for entering the bores of drill steels, of means for supporting drill steels with their ends in line with the punch pin to permit the same to enter the bores thereof, means for

causing a relative movement between the punch pin carrier and the support toward and from each other for the purpose of entering the pin into the bores of the steels and withdrawing it therefrom, a fluid operated hammer, and means for causing the hammer to be operated and cooperate with the moving means during the relative movement of the carrier and support towards each other to introduce the punch pin into the bores of drill steels and during their relative movement away from each other in dislodging the pin from the drill steels.

64. In apparatus of the character set forth, the combination with a punch pin for

entering in the bore of a drill steel, of means for holding steels with their ends in a position to receive the punch pin, fluid operated means for advancing the punch pin to move it into the steel and for withdrawing it from the steel, a fluid operated hammer, and means for supplying fluid to the fluid operated means, and simultaneously to the hammer to operate both and cause them to cooperate in moving the punch pin into the drill steels and in withdrawing the punch pin therefrom.

In testimony whereof, I affix my signature.

GUSTAVE M. NELL.
